ROLLING MILL MANDREL

Samuel E. Diescher, Pittsburgh, Pa., assignor to
 Diescher Tube Mills, Inc., Pittsburgh, Pa., a corporation of Delaware

Application May 3, 1933, Serial No. 669,145

7 Claims. (Cl. 78—103)

My invention relates to mandrels for use in reducing the wall thickness of and elongating tubular blanks, and particularly to mandrels for use in producing tubes of relatively large diameters by cross-rolling.

In reducing the wall thickness and increasing the length of a tubular blank by cross-rolling the blank on a mandrel, it is necessary to employ a mandrel having an outside diameter which is not much less than that of the interior of the completed tube. It will be appreciated that the weight of solid mandrels becomes proportionately greater relative to that of the tube as the diameter of the tube increases.

In the operation of cross-rolling large diameter tubes, no very great difficulty is experienced in introducing solid mandrels of the necessary diameter into the cross-rolls with the work-piece, but the weight of these mandrels is such that they become difficult to convey and may damage the hot walls of completed thin wall tubes as they issue from the cross-rolls upon a delivery table or other apparatus.

In order to avoid the use of a solid mandrel of large diameter and at the same time provide a mandrel that is of sufficient strength throughout its length to resist the forces exerted by the wall-reducing rolls upon the tubular blank in passing therethrough, I provide a mandrel of hollow construction but provided with simple and efficient reinforcing means that is of such shape and construction as to provide greater strength than an equivalent amount of solid material. Mandrels of this kind are adapted for cooling internally.

In accordance with my invention, the interiors of the mandrels are gilled, that is, provided with a series of alternate circumferentially-extending ribs and grooves which provide greater strength for resisting the pressures of the cross-rolls than would be afforded by the same amount of solid material. These ribs and grooves may be of various construction and form such as annular or helical. Furthermore, the ribs and grooves may be formed directly upon the interior surfaces of the mandrels, or they may be provided upon the interior surfaces of a series of removable bushings.

Although especially intended for reducing the wall thickness and increasing the length of large diameter tubular blanks in cross-rolling elongating mills, mandrels of the invention are adapted for use in treating large diameter tubes in other types of mills.

The details of my invention will be described

in connection with the accompanying drawing, in which,

Figure 1 is a view partially in horizontal section and partially in plan of a portion of a tubular blank provided with a mandrel embodying one form of my invention, the blank being between the cross-rolls in an intermediate stage of its elongation and the reduction of its wall thickness;

Fig. 2 is a transverse section of the tubular blank and mandrel of Fig. 1 and associated apparatus;

Fig. 3 is a view similar to Fig. 1 of a modification;

Fig. 4 is a transverse sectional view of the tubular blank and apparatus of Fig. 3;

Fig. 5 is a longitudinal sectional view of the forward portion of the mandrel of Fig. 3;

Fig. 6 is a view similar to Fig. 1 of a further modification; and

Fig. 7 is a transverse sectional view of the tubular blank and apparatus of Fig. 6.

Referring particularly to Figs. 1 and 2, mandrels according to the invention may be used in reducing the wall thickness and increasing the length of tubular blanks in a cross-roll mill such, for example, as that shown and described in my Patent No. 1,870,209, granted August 2, 1932. Such a mill comprises two helically acting cross-rolls 1, only portions of which are shown, and two driven rotatable guide discs 2 which engage the blank between the cross-rolls 1. A tubular blank 3 is shown in an intermediate stage of its passage through the mill, and a mandrel 4 according to the invention is shown within the blank.

The mandrel 4 comprises a hollow cylindrical member 5 that is provided upon its interior with helical ribs 6 and intervening grooves 7 that extend substantially throughout the length of the mandrel. The ribs 6 and grooves 7 therebetween most desirably extend radially for a distance that is relatively greater than the thickness of the solid portion of the hollow member 5.

The forward end of the mandrel 5 may be provided with a suitable hollow conical head such as the head 8 shown in Fig. 5 in connection with the mandrel of Figs. 3 and 4. It will be noted that the head 8 has a screw-threaded connection to the body of the mandrel and is prevented from rotation relatively thereto by a rivet 9.

In order that the mandrel may be maintained at as low a temperature and consequently at a strength that is as high as feasible, it is desirable to provide a cooling system therefor. In the

construction shown, cooling water or other suitable cooling medium is supplied to the interior of the hollow member 5 by means of a centrally disposed pipe or tube 10 that is spaced from the surrounding walls by means of supports comprising radial members 11 for engaging the tops of the ribs 6. The open forward end of the tube 10 is adjacent to the conical head 8 and the return path for the cooling water is the space 10 around the tube 10 including the grooves 7.

The ribs 6 constitute reinforcing means for the hollow member 5, and their effect is to give the mandrel a compression-resisting strength which is greater than if the thickness of the hollow member 5 were increased by an equivalent amount of solid material. The spaced ribs 6 increase the area of surface contact between the walls of the hollow member 5 and the cooling water, and the flow of the latter is facilitated by the 20 helical shape of the grooves 7. When the pipe 10 is of relatively small diameter, water may be supplied thereto under relatively high pressure in order to provide sufficiently rapid outward flow of water in contact with the surfaces to be cooled.

Reference may now be had to Figs. 3, 4 and 5, in which a modification of my invention is illustrated. Similar numerals designate like parts.

This embodiment of my invention differs principally from that of Figs. 1 and 2 in that the 30 helical ribs and grooves 6 and 7 are provided upon the interior of a series of cylindrical bushings 12 which occupy the interior of a relatively thin shell 13 of a mandrel 14. Also, the mandrel 14 is provided with a pipe 15 for cooling water that is larger than the pipe 10 previously referred to.

The bushings 12 may be of relatively short length and may be inserted in the bore of the tube 13 until the latter is reinforced throughout 40 substantially its entire length. The principal advantages of this type of construction are that the bushings 12 are removable and in case of wear of the shell or of damage either to the shell or the bushings, any of these parts may be removed to the extent that is necessary to replace them. The shell 13 may be of the same or different 45 materials, and each may be of such material as will best serve under the pressure and temperature conditions to which the mandrel is subjected.

The cooling system for the mandrel 14 of Figs. 3, 4 and 5 is substantially like that described in connection with the mandrel 4 of Fig. 1, the cooling liquid entering through the tube 15 and returning in contact with the surfaces of the ribs 55 and grooves in the bushings 12. In this arrangement, however, the supply tube is larger and the pressure may be adjusted to insure sufficiently rapid outward flow of a relatively thin film of water over the inner edges of the ribs. The bushings 12 conduct heat inwardly from the shell 13.

The construction of the mandrel 16 of Figs. 6 and 7 differs from that of the mandrel 14 of Fig. 3 principally in that the series of circumferentially-extending ribs 17 and grooves 18 with which 60 bushings 19 are provided are annular rather than helical, and the bushings 19 are shorter than the bushings 12 of Fig. 3. The length of these bushings will, however, be governed by the conditions governing their manufacture and the materials employed. Otherwise, the mandrel 16 does not differ materially from the mandrel 14. The cooling system is similar to that of the mandrel of Fig. 1.

75 The mandrels may be mounted in any suit-

able manner for the purpose of providing connections to a source of water under pressure. For example, the mandrels may be secured to a mandrel head on a suitable reciprocable carriage, the mandrel head being provided with suitable connections for continuing the supply of water during longitudinal movement and rotation of the mandrel. An arrangement of this character is shown and described in the copending application of August P. Diescher, Serial No. 662,659, filed March 25, 1933. Any other suitable mechanism may be employed for controlling the movements of the mandrels or for supplying cooling water thereto, but such mechanisms constitute no part of the present invention.

Mandrels constructed in accordance with my invention are relatively light in weight while affording sufficient strength to resist the forces exerted by cross-rolls in elongating a tubular blank upon the mandrel. The ribs provide reinforcing means for the wall of the hollow cylindrical member, the strength afforded by the ribs exceeding that given by an equivalent amount of metal in the form of added wall thickness.

Furthermore, the provision of a series of ribs 25 and grooves throughout the interior of the mandrel, whether or not bushings are employed, very materially increases the area of surface contact with the cooling medium and accordingly facilitates the transfer of heat to the latter.

The employment of separate bushings for reinforcing a relatively thin hollow shell renders it unnecessary, in case of wear or damage to a portion of the mandrel, to discard the entire device as might be necessary when the outer shell is unitary with its reinforcing means.

The foregoing and other advantages will be apparent to those skilled in the art of construction and operation of apparatus for reducing and elongating tubular blanks upon mandrels.

I claim:

1. A mandrel for use in reducing the wall thickness and increasing the length of tubular blanks comprising a hollow elongated body proper of substantially uniform cross section and closed at one end thereof, helical ribs extending inwardly from the internal surface of said body and substantially along the length thereof to provide a central unobstructed passageway and a helical passageway in the grooves between said ribs, and means for circulating a cooling medium along said passageway and said grooves.

2. A mandrel for use in reducing the wall thickness and increasing the length of tubular blanks comprising a hollow elongated body proper of substantially uniform cross section and closed at one end thereof, a series of hollow bushings within said body, and substantially throughout the length thereof, said bushings being provided with inwardly extending ribs and grooves alternating therewith to provide an unobstructed central passageway, and means for circulating a cooling medium along said passageway and in the grooves communicating therewith.

3. A mandrel for use in reducing the wall thickness and increasing the length of tubular blanks comprising a hollow elongated body proper of substantially uniform cross section and closed at one end thereof, a series of hollow bushings within said body, and substantially throughout the length thereof, said bushings being provided with inwardly extending helical ribs and grooves alternating therewith to provide a central passageway communicating with said grooves, and means

for circulating a cooling medium through said passageway.

4. A mandrel for use in reducing the wall thickness and increasing the length of tubular blanks, comprising an elongated tubular body of substantially uniform cross section, the interior of the body being provided with annularly-disposed ribs extending inwardly from the internal surface thereof and throughout substantially the entire length thereof and formed to reinforce said body against pressure applied laterally of it.

5. A mandrel for use in reducing the wall thickness and increasing the length of tubular blanks, comprising an elongated tubular body of substantially uniform cross section, the interior of the body being provided with helical ribs extending inwardly from the internal surface thereof and throughout substantially the entire length thereof and formed to reinforce said body against pressure applied laterally of it.

6. A mandrel for use in reducing the wall thick-

ness and increasing the length of tubular blanks, comprising an elongated tubular body of substantially uniform cross section, a series of hollow bushings fitted within said body and extending throughout substantially the entire length thereof, said bushings being provided with annularly-disposed ribs formed to reinforce said body against pressure applied laterally to it.

7. A mandrel for use in reducing the wall thickness and increasing the length of tubular blanks, comprising an elongated tubular body of substantially uniform cross section and closed at one end thereof, annularly-disposed body-reinforcing ribs extending inwardly from the internal surface of said body and throughout substantially the entire length thereof to provide a central unobstructed passageway and an annularly-disposed passageway in the grooves between said ribs, and means for circulating a cooling medium along said passageway and grooves.

SAMUEL E. DIESCHER.
